UNITED STATES PATENT OFFICE

2,092,629

PUMP

Herbert Allen, Houston, Tex., assignor, by mesne assignments, to Abercrombie Pump Company, Houston, Tex., a corporation of Texas

Application May 14, 1934, Serial No. 725,569

20 Claims. (Cl. 103—44)

This invention relates generally to pumps.

It will be found particularly useful in pumps designed for pumping abrasive and corrosive fluid of the general type disclosed by Letters 5 Patent of the United States to Stephens No. 1,848,441 of March 8, 1932. A conventional pump of this type adapted for use as a mud or slush pump in deep well drilling includes a barrel; inlet and outlet valves therefor; a hollow expansible 10 member within the barrel; and a reciprocable piston to actuate pumping fluid confined within the expansible member to cause expansion and contraction thereof whereby pumped fluid is drawn into and forced out of said barrel.

15 In pumps of other types the pumped fluid is in contact with the piston and rod and carries away the heat generated by the reciprocation of the piston and rod through conventional packings. In the type of pump to which this invention relates, however, the piston and rod are sealed off from the fluid being pumped and the heat so generated is therefore transferred to the pumping fluid within the expansible member. These 20 expansible members are usually made of rubber, which is a very good heat insulator, and the pumping fluid within the expansible member is in contact with very little metal. Under certain 25 conditions, such as when the packings are inadvertently made too tight, the heat is not dissipated as rapidly as it is generated. And so, under such 30 conditions, the pumping fluid in the expansible member will reach a very high temperature whereby the expansible member will be injured; and when the pressure on the pumping fluid is 35 reduced on the suction stroke of the piston, the pumping fluid will boil so that the pumping member will remain expanded, which renders the pump inoperative.

This invention has for its general object the 40 provision of new and improved means to prevent heating of the pumping fluid to an objectionably high temperature by cooling the pumping fluid to remove the heat as it is generated.

A specific object of the invention is to provide 45 means to so cool the pumping fluid with the pumped fluid as a coolant.

Another specific object is to so cool the pumping 50 fluid by circulating therethru but not in contact therewith a coolant from an external source independently of the pump.

A further specific object is to prevent the attainment 55 of an objectionably high temperature of the pumping fluid in either of the pumping members of a double barrel pump, by providing a new and improved cooler disposed in one of

said members and extending into a hollow piston which in turn extends into the other of said members.

The invention also has for another of its objects the provision of new and improved means whereby the pumping fluid may be kept above its freezing point, or at any desired predetermined temperature, when pumps of this character are operated in very low temperatures.

Other objects will hereinafter appear.

The preferred embodiment of the invention is illustrated by the accompanying drawing which is a partly sectional elevation of the pump.

As the operation of this pump is clearly set forth in said patent to Stephens No. 1,848,441, it 15 will be but briefly referred to here as follows:

The two barrels of the pump are indicated at 1 and 2. The inlet and outlet means for the former are indicated at 3 and 4, respectively; and for the latter at 5 and 6, respectively. The inlet means 3 and 5 communicate with a common inlet passageway 7, and outlet means 4 and 6 with a common outlet passageway 8. Within the barrels 1 and 2 are hollow expansible pumping members 9 and 10, the former being sealed at its opposite 20 ends to the end walls of the barrel 1 at 11 and 12, and the latter being sealed at its opposite ends to the end walls of the barrel 2 at 13 and 14. The numerals 15, 16, 17 and 18 indicate rings 25 whereby the expansible members 9 and 10 are connected to the end walls of the barrel. These 30 will form the subject matter of another application.

The piston is indicated at 19 extending through 35 the packings 20 and 21 into the expansible members 9 and 10, said packings 20 and 21 being held in place by means of the glands 22 and 23 secured by the ring nuts 24 and 25. Extending from the piston 19 through the packing 26 is the 40 rod 28.

The piston 19 may be reciprocated by the rod 28 and it will serve to displace the pumping fluid 45 confined within the expansible members 9 and 10 to alternately expand and contract said members. When the piston 19 is in the position shown the pumping member 10 is in its normal cylindrical shape, and the pumping member 9 is in its expanded shape. When the piston moves to the right the pumping member 10 will be expanded, and the pumping member 9 will resume its normal cylindrical shape. The valves (not shown) of the inlet means 5 and outlet means 4 will then be closed, and the valves (not shown) of the inlet means 3 and outlet means 6 will be open, 50 so that the pumped fluid confined in the barrel 55

2 will be expelled through the outlet means 6 and passageway 8, and a fresh charge of pumped fluid will be drawn into the barrel 1 through the inlet passageway 7 and inlet means 3. When 5 the piston 19 moves in the opposite direction into the position shown by solid lines, the valves (not shown) of the inlet means 5 and outlet means 4 will open, and the valves (not shown) of inlet means 3 and outlet means 6 will close, 10 so that the pumped fluid within the barrel 1 will be expelled through the outlet means 4 and passageway 8, and a fresh charge of fluid will be drawn into the barrel 2 through the inlet passageway 7 and inlet means 5. It will be obvious 15 that as the piston 19 reciprocates, this operation will be repeated.

Referring now to the new and improved means provided by this invention to prevent heating of the pumping fluid confined within the pumping 20 members 9 and 10 to an objectionably high temperature by the reciprocation of the piston 19 and rod 28 through the packings 20, 21 and 26.

It will be noted that the piston 19 is hollow, 25 and that end adjacent the pumping member 10 is open. The numeral 30 indicates a cooler, which, in the form shown, comprises a bent pipe supported by the end wall of the barrel 2 and extending inwardly thru pumping member 10 into piston 19 to a point adjacent packings 20 and 30 21. The cooler is connected by the pipes 31 and 32 to the outlet passageway 8, and by the pipes 33 and 34 to the inlet passageway 7. The cooler 30 is also connected by the pipes 31 and 35 and by the pipes 33 and 36 to an external coolant 35 source of supply, including the coolant pump 37. The pipes 32, 34, 35 and 36 are provided with valves 38, 39, 40 and 41, as shown.

Now if the valves 40 and 41 are closed, and the 40 valves 38 and 39 opened, a portion of the pumped fluid discharged thru the outlet passageway 8 will pass thru the pipes 32 and 31 into the cooler 30, and thence thru the pipes 33 and 34 into the inlet passageway 7. As the hollow piston 19 extends into both pumping members 9 and 10 and 45 the cooler extends thru the pumping fluid in pumping member 10 and into piston 19 to a point adjacent packings 20 and 21, the pumping fluid in both members 10 and 11 will be thereby prevented from attaining objectionably high 50 temperatures.

If the valves 38 and 39 are closed and valves 40 and 41 are opened, and the coolant pump 37 operated, a coolant may be forced from an external source of supply through the pipes 35 and 31 55 into the cooler 30 (to prevent the excessive generation of heat) and thence thru the pipes 33 and 36 back to the source of coolant supply.

It will be apparent in view of the foregoing 60 that the heat is efficiently removed from the pumping fluid in the expansible members 9 and 10 as it is generated by the piston and rods and their packings.

It will be understood that if the pump is operated in a very low temperature so that there 65 exists danger of freezing of the pumping fluid, or of lowering of the temperature thereof to an objectionably low point, the valves 38 and 39 may be closed and the valves 40 and 41 opened, 70 and the pump 37 operated to force a heating fluid from an external source of supply through the pipes 35 and 31 into the pipe 30 (the pipe 30 then serving as a heater to raise the temperature 75 of the pumping fluid within the expansible members 9 and 10) and thence through the pipes

33 and 36 back to the source of heating fluid supply.

The invention is not limited to the preferred embodiment here disclosed. Various changes will occur to those skilled in the art, and may be made 5 within the scope of the following claims:

I claim:

1. A pump having a pair of barrels; inlet and outlet means for said barrels; a hollow expansible pumping member in each of said barrels; 10 pumping fluid in said members; piston packings in said barrels; a piston extending through said packings into said members and reciprocable to actuate said pumping fluid to effect the expansion and contraction of said members to draw 15 pumping fluid into said barrels through said inlet means, and to expel it from said barrels through said outlet means; said piston being hollow; and a cooler mounted in one end of one of said barrels and extending through the expansible member 20 in said barrel into said piston to a point adjacent said packings; said cooler communicating with said inlet means and outlet means so that a portion of the pumped fluid discharged through said outlet means will pass through said cooler and 25 into said inlet means.

2. A pump having a pair of barrels; inlet and outlet means for said barrels; a hollow expansible pumping member in each of said barrels; pumping fluid in said members; piston packings 30 in said barrels; a piston extending through said packings into said members and reciprocable to actuate said pumping fluid to effect the expansion and contraction of said members to draw 35 pumping fluid into said barrels through said inlet means, and to expel it from said barrels through said outlet means; said piston being hollow; and a cooler mounted in one end of one of said barrels and extending through the expansible member 40 in said barrel into said piston to a point adjacent said packings; said cooler communicating with said outlet means so that a portion of the pumped fluid discharged through said outlet means will pass through said cooler.

3. A pump having a pair of barrels; inlet and 45 outlet means for said barrels; a hollow expansible pumping member in each of said barrels; pumping fluid in said members; piston packings in said barrels; a piston extending through said packings and reciprocable to actuate said pumping 50 fluid to effect the expansion and contraction of said members to draw pumping fluid into said barrels through said inlet means, and to expel it from said barrels through said outlet means; said piston being hollow; and a cooler extending 55 through the expansible member in one of said barrels into said piston to a point adjacent said packings; said cooler communicating with said outlet means so that a portion of the pumped fluid discharged through said outlet means will 60 pass through said cooler.

4. A pump having a pair of barrels; inlet and outlet means for said barrels; a hollow expansible pumping member in each of said barrels; pumping fluid in said members; piston packings 65 in said barrels; a piston extending through said packings and reciprocable to actuate said pumping fluid to effect the expansion and contraction of said members to draw pumping fluid into said barrels through said inlet means, and to expel 70 it from said barrels through said outlet means; a cooler extending into the expansible member in one of said barrels and communicating with said outlet means so that a portion of the pumped fluid discharged through said outlet means will 75 pass through said cooler.

5. A pump having a pair of barrels; inlet and outlet means for said barrels; a hollow expansible pumping member in each of said barrels; pumping fluid in said members; piston packings in said barrels; a piston extending through said packings into said members and reciprocable to actuate said pumping fluid to effect the expansion and contraction of said members to draw pumping fluid into said barrels through said inlet means, and to expel it from said barrels through said outlet means; said piston being hollow; and a cooler mounted in one end of one of said barrels and extending through the expansible member in said barrel into said piston to a point adjacent each of said packings; and means to circulate a coolant thru said cooler independently of said pump.

6. A pump having a pair of barrels; inlet and outlet means for said barrels; a hollow expansible pumping member in each of said barrels; pumping fluid in said members; piston packings in said barrels; a piston extending through said packings and reciprocable to actuate said pumping fluid to effect the expansion and contraction of said members to draw pumping fluid into said barrels through said inlet means, and to expel it from said barrels through said outlet means; a cooler extending into the expansible member in one of said barrels and means to circulate a coolant thru said cooler independently of said pumps.

7. A pump having a barrel; inlet and outlet means for said barrel; a hollow expansible pumping member in said barrel; pumping fluid in said member; a piston packing; a piston extending through and reciprocable in said piston packing to actuate said pumping fluid to effect the expansion and contraction of said member to draw pumped fluid into said barrel through said inlet means and to expel it from said barrel through said outlet means; said piston being hollow; and a cooler mounted in said barrel and extending through said member into said piston to a point adjacent said packing; said cooler communicating with said inlet and outlet means so that a portion of the pumped fluid discharged through said outlet means will pass through said cooler and into said inlet means.

8. A pump having a barrel; inlet and outlet means for said barrel; a hollow expansible pumping member in said barrel; pumping fluid in said member; a piston packing; a piston extending through and reciprocable in said piston packing to actuate said pumping fluid to effect the expansion and contraction of said member to draw pumped fluid into said barrel through said inlet means and to expel it from said barrel through said outlet means; said piston being hollow; and a cooler mounted in said barrel and extending through said member into said piston to a point adjacent said packing; said cooler communicating with said outlet means so that a portion of the pumped fluid discharged through said outlet means will pass through said cooler.

9. A pump having a barrel; inlet and outlet means for said barrel; a hollow expansible pumping member in said barrel; pumping fluid in said member; a piston packing; a piston extending through and reciprocable in said piston packing to actuate said pumping fluid to effect the expansion and contraction of said member to draw pumped fluid into said barrel through said inlet means and to expel it from said barrel through said outlet means; said piston being hollow; a cooler mounted in said barrel and extending through said member into said piston to a point

adjacent said packing; and means to circulate a coolant thru said cooler.

10. A pump having a barrel; inlet and outlet means for said barrel; a hollow expansible pumping member in said barrel; pumping fluid in said member; a piston packing; a piston extending through and reciprocable in said piston packing to actuate said pumping fluid to effect the expansion and contraction of said member to draw pumped fluid into said barrel through said inlet means and to expel it from said barrel through said outlet means; said piston being hollow; a cooler extending into said member and said piston; and means to circulate a coolant thru said cooler.

11. A pump having a barrel; a hollow expansible pumping member in said barrel; pumping fluid in said member; a piston to actuate said pumping fluid; a cooler extending into said member and said piston; and means to circulate a coolant thru said cooler.

12. A pump having a barrel; an expansible pumping member in said barrel; pumping fluid in said member; means to actuate said pumping fluid to cause said member to pump fluid through said barrel; and a cooler in said member and communicating with said barrel so that a portion of the pumped fluid discharged by said barrel will pass through said cooler.

13. The method of controlling the temperature of pumping fluid actuated within a hollow expansible pumping member to expand and contract said member, which consists in subjecting said pumping fluid to the cooling action of the fluid being pumped by passing a portion of the pumped fluid through but not in contact with said pumping fluid.

14. A pump having a barrel; an expansible pumping member in said barrel; pumping fluid in said member; means to actuate said pumping fluid to cause said member to pump fluid through said barrel; a heater in said member; and means to introduce a heating fluid into said heater.

15. A pump having a barrel; an expansible pumping member in said barrel; pumping fluid in said member; means to actuate said pumping fluid to cause said member to pump fluid through said barrel; and a heater in said pumping fluid to keep said pumping fluid at a predetermined temperature.

16. A pump having a barrel; an expansible pumping member sealed in said barrel; pumping fluid in said member; means to actuate said pumping fluid to cause said member to pump fluid through said barrel; a heat transfer unit interiorly of said expansible member; a fluid medium passing through said heat transfer unit; said unit arranged to effect a heat transfer between the pumping fluid in said expansible member and the fluid medium in said heat transfer unit.

17. A pump having a barrel; an expansible pumping member sealed in said barrel; pumping fluid in said member; means to actuate said pumping fluid to cause said member to pump fluid through said barrel; heat transfer means interiorly of said expansible member; a fluid medium passing through said heat transfer means; said last named means arranged to effect a heat transfer between the pumping fluid in said expansible member and the fluid medium in the heat transfer means.

18. A pump having a barrel, an expansible pumping member in said barrel, pumping fluid in said member, means to actuate said pumping

fluid to cause said member to pump fluid through said barrel, and means for passing through the pumping fluid but out of intimate contact therewith a fluid medium of different temperature from said pumping fluid to regulate the temperature of said pumping fluid.

19. A pump having a barrel, inlet and outlet means for said barrel, a hollow expansible pumping member in said barrel, pumping fluid in said member, a piston packing, a piston extending through and reciprocable in said piston packing to actuate said pumping fluid to effect the expansion and contraction of said member to

draw pumped fluid into said barrel through said inlet means, and to expel it from said barrel through said outlet means, said piston being hollow, and means to circulate a cooling fluid through said piston.

20. A pump having a hollow expansible pumping member, a pumping fluid in said member, a piston movable in said pumping fluid to actuate said pumping member, and means to cause the fluid pumped by said member to circulate through the interior of said piston.

HERBERT ALLEN.
